UNITED STATES PATENT OFFICE.

EDWARD McGUIRE JONES, OF WINCHESTER, KENTUCKY.

COMB.

1,226,527.

Specification of Letters Patent.

Patented May 15, 1917.

Application filed May 17, 1915. Serial No. 28,571.

To all whom it may concern:

Be it known that I, EDWARD M. JONES, a citizen of the United States, and a resident of Winchester, in the county of Clark and State of Kentucky, have invented an Improvement in Combs, of which the following is a specification.

This invention relates to improvements in toilet articles, and more particularly to a fountain comb adapted for use in the treatment of the hair and scalp.

One object of the invention is to provide a hollow body portion through which is fed air under pressure and medicinal compounds, such as salve and ointments, for distribution to the several teeth of the comb whereby the scalp and hair may be effectively treated.

Another object is the provision of suitable means for shutting off the supply of medicament to the teeth so that the air pressure alone may be utilized for cleansing and drying the hair.

A still further object is to provide a device of this character which is simple in construction, thus reducing the cost of manufacture to a minimum, and one which is effective in carrying out the purpose for which it is designed.

The inventive idea involved is capable of receiving a variety of mechanical expressions, one of which, for the purpose of illustrating the invention, is shown in the accompanying drawing, in which—

Figure 1 is a top plan view of the comb, partly broken away.

Fig. 2 is a side elevation thereof, parts being shown in section, and

Fig. 3 is a transverse sectional view.

Referring more particularly to the accompanying drawing in which like reference characters indicate similar parts, the numeral 1 indicates the body portion of the comb which is hollow throughout its entire length and which has a plurality of alined teeth 2 having longitudinally extending ducts or passages 3 therein. The body portion is also provided with a plurality of small openings 3' arranged in staggered relation between the teeth 2, for a purpose which will later appear.

Diametrically disposed to the teeth 2, the body portion 1 has mounted in an opening therein the extension 4 of a globe coupling 5. The latter is also provided with another extension 6 which is in substantially parallel

relation with the body portion 1 when the coupling is in the position shown and which has connected thereto, by means of a union 7, one end of the flexible tubing 8, the other end of which is attached to a suitable source of air supply, not shown.

The coupling 5 is provided with a threaded opening 9 diametrically disposed to the extension 4, said opening having mounted therein the threaded reduced portion 10 of the reservoir or cup 11 which has the removable cover 12 whereby a supply of salve or ointment may be placed therein. A duct or passage 13 is formed in the portion 10 and communicates with the reservoir 11 and said portion 10 is further reduced and extended to provide an elongated tube 14 which extends through the coupling 5 and portion 4 and projects into the body 1. A needle valve 15 is mounted in the cover 12 of the reservoir and adapted to control the passage of the contents thereof through the duct 13 and tube 14 into the body portion 1. The latter has mounted therein the longitudinally extending baffle plate 16 which is arranged adjacent the inner tube 14 and in the path of the flow therefrom.

In practice, should it be desired to treat the hair or scalp with the contents of the reservoir, the valve 15 is adjusted so as to regulate the flow of said contents therefrom into the tube 14 from whence it will drop upon the baffle plate 16 and be distributed to the ends of the comb as well as the central portion thereof. In order to facilitate the distribution, the source of air supply may be turned on and the air under pressure fed through the flexible tubing 8 into the coupling 5 and thence through the extension 4 into the body portion 1 of the comb where it strikes the baffle plate 16 and assists in distributing the medicament into the different teeth 2 and through openings 3'.

Should it be desired to dispense with the use of the contents of the reservoir and merely dry or clean the hair, the needle valve 15 may be adjusted to close the opening in the reservoir 11 in order that the air supply alone will be fed into the body portion 1 and through the teeth 2 and openings 3'.

I claim:

A comb comprising a hollow, elongated body portion having staggered openings, teeth arranged between said openings and having ducts therein, a coupling carried by said body portion medially the ends thereof,

- a flexible connection attached to said coupling for feeding air into said body portion and through said openings, a reservoir carried by said coupling and having a tube 5 projecting into said body portion intermediate its ends, and a baffle plate arranged in said body portion below said tube, the ends of said plate terminating short of the ends of said body portion.

EDWARD McGUIRE JONES.
